Term of patent 14 years

(Cl. D1—12)

Fig. 1

Fig. 2

Fig. 3

Fig. 4

FIG. 1 is a perspective view of an illuminable display sign showing my new design,

FIG. 2 is a front elevational view of the same,

FIG. 3 is a side elevational view of the same, and

FIG. 4 is a top plan view of the same.

The dominant features of my design reside in the portions shown in full lines, said portions being characterized by the specific rectangular hip roof having a horizontal top ridge, a short vertical wall at about mid-height and predominant eaves, and being further characterized by a sign holding element with sloping side surfaces and rectangular windows.

I claim:

The ornamental design for an illuminable display sign, as shown and described.
